PHOTOGRAPHIC COPYING APPARATUS

Charles J. Young, Princeton, N.J., assignor to Radio Corporation of America, a corporation of Delaware

Filed June 21, 1961, Ser. No. 65,667

Term of patent 14 years

(Cl. D61—1)

FIGURE 1 is a perspective view of a photographic copying apparatus, showing my new design;

FIGURE 2 is a front elevational view;

FIGURE 3 is a top plan view;

FIGURE 4 is a rear elevational view, showing a holding plate in its open position;

FIGURE 5 is an elevational view looking from the right of FIGURE 4;

FIGURE 6 is an elevational view looking from the right of FIGURE 2;

The broken-line showing of a book in FIGURES 1, 2, 3, 4 and 5 and the broken-line showing of a sheet of photocopy paper in FIGURES 1, 2 and 6 are for illustrative purposes only.

The dominant features of my design reside in the portions shown in full line on the drawings.

I claim:

The ornamental design for a photographic copying apparatus, substantially as shown and described.
